UNITED STATES PATENT OFFICE.

ALONZO CHAPPEL, OF BROOKLYN, NEW YORK.

COMBINATION-EASEL.

SPECIFICATION forming part of Letters Patent No. 258,990, dated June 6, 1882.

Application filed October 8, 1881. (No model.)

To all whom it may concern:

Be it known that I, ALONZO CHAPPEL, of Brooklyn, in the county of Kings and State of New York, have invented a new and Improved Combination-Easel, of which the following is a full, clear, and exact specification.

My invention consists of a parlor or drawing-room piece combining an easel, drawing board or table, portfolio, and drawers; of a novel means of securing the canvas or drawing-paper to the drawing-board or easel without the use of thumb-tacks, and of novel means for supporting mounted canvas or paper or other foundation of the picture upon the easel.

Reference is to be had to the accompanying drawings, forming a part of this specification, in which similar letters of reference indicate corresponding parts in all the figures.

Figure 1 is a front elevation of my combination-easel as it appears when folded up. Fig. 2 is a vertical section taken on the line *y* *y* of Fig. 3, the easel being raised to position for use. Fig. 3 is a vertical cross-section taken on the line *x* *x* of Fig. 1, looking toward the rear of the easel. Fig. 4 is an edge view of the easel. Fig. 5 is a front elevation of the easel or drawing-board, showing my improved means of holding the canvas or drawing-paper; and Fig. 6 is an edge or top view of the same.

The frame of the easel is composed of the uprights *A* and *A'*, tied together near their lower ends by the cross-piece *B* and at their upper ends by the bottom board of the shallow box *D*. Upon one edge of this shallow box is hinged the easel *E*, and between the uprights and upon the cross-piece *B* is placed the portfolio *F*. The uprights of the frame are made quite narrow, and are divided at the bottom to form the legs *c* *c'*, which may be provided with casters, as shown, and the portfolio is made narrow to correspond with the uprights, as shown in Fig. 3, and it is closed by the hinged door *f*, which may be provided with lock and key. Between the upper side of the portfolio and the bottom of the shallow

box *D* is placed the drawer *G*, which is divided into several compartments, as shown in Figs. 2 and 3, for holding the artist's outfit of paints, brushes, pencils, &c., when not in use, and this drawer may also be provided with lock and key.

The easel, when raised for use, is held in an inclined position, as shown in Fig. 2, by means of the jointed braces *a* *a*, which are hinged to the easel and bottom board of the shallow box *D* in such manner that they are adapted to fold back into the box *D* and permit the easel to be lowered upon the edge of the box to a horizontal position, as shown in Fig. 1.

In using the easel with mounted canvas or paper, or other foundation or material for the picture, the frame or mounting is held upon the easel by means of the cramp-plates *d* *d*, which fit upon the edges of the easel, as shown in Figs. 2 and 4; and for holding drawing-paper or other unmounted foundation I provide the cross-bars *c* *c* and the screw-clamps *g* *g*, which fit over the ends of the cross-bars and the edges of the easel and clamp the paper or canvas, as clearly shown in Figs. 5 and 6.

When not in use the clamps, cross-bars, and cramp-plates can be placed in the shallow receptacle or box *D*.

Thus constructed the device is very convenient and ornamental to the drawing-room or parlor, and occupies small space.

Having thus described my invention, I claim as new and desire to secure by Letters Patent—

1. The combination, with the shallow box *D* on the frame *A* *A'* *B*, of the hinged easel *E*, having the hinged braces *a*, the cross-bars *c*, the cramp-plates *d*, and the clamps *g*, arranged as shown and described.

2. In combination with the hinged easel *E* and the receptacle *D*, the portfolio *F* and drawer *G*, substantially as and for the purposes set forth.

ALONZO CHAPPEL.
